(57) **CLAIM**

The ornamental design for a removable contouring helmet cover, as shown and described.

DESCRIPTION

FIG. 1 is an isometric view of a removable contouring helmet cover showing my new design.

FIG. 2 is a front elevation view thereof.

FIG. 3 is a top plan view thereof.

FIG. 4 is a left side elevation view thereof.

FIG. 5 is a right side elevation view thereof.

FIG. 6 is a rear elevation view thereof; and,

FIG. 7 is a bottom plan view thereof.

The broken lines in FIGS. 1-7 are included for the purpose of illustrating use and environment and forms no part of the claimed design.
